RADIATOR AUXILIARY HEAT DISTRIBUTOR

George M. Blackford, Chicago, Ill.

Application July 16, 1954, Serial No. 443,738

1 Claim. (Cl. 257—137)

This invention relates to devices for circulating heat, particularly of radiators wherein coils or sections are heated with steam, hot water, or the like, and in particular, a housing framed over a radiator and a fan for circulating air around the coils of the radiator whereby the air passes through openings in the lower end of the housing so that heat is distributed over the lower part of a room or enclosure.

The purpose of this invention is to provide means for increasing the efficiency of heating systems where steam, hot water, and the like supply heat to coils or sections of a radiator positioned in a room or enclosure.

In conventional heating systems where the only heat-exchanging element in a room or enclosure is a radiator heated by steam, hot water, or the like, it is necessary for air heated by the radiator to create circulation by the heated air passing upwardly, filling the upper portion of the room and whereby the cooler air is forced downwardly, eventually finding its way to the radiator by which it is heated and the cycle of circulation repeated. With this thought in mind, this invention contemplates forced draft means in combination with a radiator in which the forced draft is supplied to the upper end of the radiator and in which the only escape therefor is through openings around the bottom of the radiator. By this means air from the intermediate portion of a room is drawn into a relatively thin area around a radiator, forced downwardly and discharged into the cool portion of the room positioned around the lower part of the radiator.

The object of this invention is, therefore, to provide means for stimulating circulation of air over a radiator whereby cool air is continuously blown over a radiator and, after being heated by the radiator, is discharged in the lower part of a room or enclosure.

A further object of the invention is to provide means for circulating the air of a room or enclosure over a radiator in which air passages around sections or coils of the radiator are comparatively thin so that the air is brought into close proximity of the surface of the radiator and consequently rapidly heated in which the device is of a simple and economical construction.

With these and other objects and advantages in view, the invention embodies a housing for a radiator which, except for an inlet opening at one corner of the upper end of the radiator and an outlet opening at the foot, and across the front of the radiator, provides a complete enclosure for the radiator and in which a fan positioned in the inlet opening at the upper corner of the housing drives air around the surface areas of the radiator with the air escaping through the opening in the lower end of the front of the housing.

Other features and advantages of the invention will appear from the following description taken in connection with the drawings, wherein:

Figure 1 is a front elevational view illustrating the improved radiator housing.

Figure 2 is an end elevational view of the radiator

2

housing showing air inlet openings in the upper end and also showing a door which provides access to a steam valve handle on the lower part of the radiator.

Figure 3 is an end elevational view looking toward the opposite end of the radiator with the conventional radiator valve or vent shown in broken lines.

Figure 4 is a longitudinal section through the radiator housing taken on line 4—4 of Figure 2.

Figure 5 is a cross section through the radiator housing taken on line 5—5 of Figure 1.

Figure 6 is a typical cross section through the radiator housing showing the housing with the radiator removed and looking toward the end in which the opening for the radiator valve or vent is positioned.

Figure 7 is a sectional plan through the radiator housing taken from a point below the cover and showing the fan or blower for circulating air through the housing.

Figure 8 is a view showing a sectional plan similar to that shown in Figure 7 illustrating a modification wherein the side panels are provided with filling elements that extend into openings between the sections of the radiator, the fan housing being shown in elevation.

Referring now to the drawings wherein like reference characters denote corresponding parts, the improved radiator housing of this invention includes a front wall 10, a rear wall 11, first and second end walls 12 and 13, a cover 14, and a fan 15 which is adapted to be actuated by a motor 16.

The length of the housing is such that the end wall 12 extends beyond the steam valve 17 and the opposite end wall 13 extends beyond the vent or radiator valve 18. In order to hold the air in close proximity to the surface area of the radiator 19 over which the housing is positioned, a partition 20 is spaced from the wall 12 and a similar partition 21 is spaced inwardly from the end wall 13. Horizontally disposed supporting elements 22, 23 and 24 support the partition 20 from the end wall 12 and similar elements 25, 26 and 27 provide supporting means for a partition 21. The radiator or vent valve 18 is located between the elements 25 and 26 and the handle 28 of the steam valve 17 extends through an opening 29 in the member 24 whereby the handle 28 is positioned to register with an opening 30 in the end wall 12. The opening 30 is closed by a door 31 that

is slidably mounted in rails 32 and that is provided with a handle 33. By this means the door 31 is adapted to be moved upwardly to open the area 30 so that the handle 28 may be reached for opening and closing the valve. The lower end of the end wall 12 extends downwardly to a floor surface, as indicated by the numeral 34, and the opposite end wall 13 and also the front wall 10 terminate at a point 35 providing a continuous escape opening 36 for air from the fan 15 along the front and one end of the radiator.

The housing is provided with supporting legs, as indicated by the numeral 37, which are positioned at the four corners, and which may also be positioned at other suitable points around the housing.

The fan 15 with the motor 16 are positioned in a cylindrical band or collar 38 positioned on a thin-gauge metal perforated plate 59 attached to the inside of the end wall 12 and, as shown in Figures 2 and 5, the plate 59 is provided with openings 39 through which air is drawn by the fan and, as indicated by the arrows 40, the air from the fan is circulated over the head of the radiator and downwardly around the sections or coils thereof with the air coming in close contact with the surface of the radiator and with the heated air being discharged through the openings 36.

The housing is provided with a toggle or button switch, as indicated by the numeral 41, which, as shown in Figure 4, is mounted on the perforated plate 59 attached

to the wall 12 and the switch is connected by wires 42 to a suitable source of current supply and to the motor 16. An oil cup 43 is also positioned on the plate 59 attached to the wall 12.

The cover 14 is provided with corner lugs 44 in which dowel pins 45 are positioned and, as shown in Figure 1, the dowels which secure the cover in place extend downwardly in corner lugs, such as the lugs 44. It will be understood, however, that the cover may be secured on the upper end of the housing by other suitable means.

As illustrated in Figure 7, the front and rear walls, 10 and 11, of the housing are provided with lining sheets or panels 47 and 48, which are preferably formed of insulating material and these panels retain air being circulated through the radiator in relatively close contact with the surface area of the radiator.

In Figure 8 similar layers 49 and 50, of lining material, are placed against the inner surfaces of walls 51 and 52 of a housing having end walls 53 and 54 and the panels 49 and 50 are provided with inwardly extended tongues 55 and 56 that partially fill triangular-shaped areas between the sections of the radiator. In this design the housing is provided with a fan 57 by which air is circulated through the housing, and the lower edge of the front wall and end opposite to that in which the fan is positioned are spaced above the floor providing outlet areas therein.

The partition 21, spaced from the end wall 13 of the housing is provided with an opening 58 which is positioned to receive the air valve or vent 18 as the parts are assembled.

In order to obtain efficiency in heating systems, particularly for residences, it is essential that air be circulated over the hot areas of a radiator as quickly as possible as with the air traveling continuously heat units, imparted thereto, are evenly distributed throughout a room or other area in which the device is positioned.

It will be understood that other modifications, within the scope of the appended claim, may be made in the design and arrangement of the parts without departing from the spirit of the invention.

What is claimed is:

In a circulating housing for use on a radiator, the combination which comprises a front wall, a rear wall, and first and second end walls the lower edge of the

front wall being spaced upwardly from a floor upon which the housing is positioned, providing an outlet opening at the front and in the lower part of the housing, the first end wall being positioned at the end of the housing in which a supply valve of the radiator over which the housing is mounted is positioned, a transversely positioned vertically disposed partition supported by horizontally disposed elements extended between said first end wall and the partition, the lower portion of said first end wall having an opening therein to provide access to a supply valve of a radiator over which the housing is positioned, a door slidably mounted on said first end wall and positioned to cover said opening, said first end wall also having air inlet openings in the upper part, a fan mounted to draw air through the air inlet openings of the first end wall discharging the air into the housing, the second end wall being positioned at the end of the radiator on which a vent valve is positioned, and the lower edge of the second end wall terminating at a point spaced upwardly from a floor upon which the housing is positioned also providing an outlet opening, a transversely disposed vertically positioned partition spaced inwardly from said second end wall, a cover positioned on the housing, and lining panels of insulating material positioned on inner surfaces of the front and rear walls forcing all air being circulated through the housing into close proximity with a radiator therein, the fan positioned to draw air through the said air inlet openings being relatively small whereby air is circulated through the housing and over a radiator therein at comparatively low velocity.
